United States Patent Office

Des. 215,411
Patented Sept. 30, 1969

215,411

JUG

David L. Anderson, Ballwin, Mo., assignor to Monsanto Company, St. Louis, Mo., a corporation of Delaware

Filed May 22, 1968, Ser. No. 12,038

Term of patent 14 years

Int. Cl. D9—01

U.S. Cl. D9—47

FIG. I

FIG. II

FIG. III

FIG. IV

FIG. I is a perspective view of a jug showing my new design;

FIG. II is an elevational view of the jug of FIG. I;
FIG. III is a top plan view of the jug of FIG. I; and
FIG. IV is a sectional view taken through the line
IV—IV of FIG. II.

I claim:

The ornamental design for a jug, substantially as
shown.
